CLAIM

The ornamental design for a electronic controlled faucet, as shown and described.

DESCRIPTION

FIG. 1 is a left side elevational view of an electronic controlled faucet showing our new design, the right side being a mirror image of the left side;

FIG. 2 is a front elevational view thereof;

FIG. 3 is a top plan view thereof;

FIG. 4 is a bottom plan view thereof; and,

FIG. 5 is a rear elevational view thereof.

Fig. 1.Fig. 2.Fig. 3.

Fig. 4.

Fig. 5.
